UNITED STATES PATENT OFFICE

121,097

DESIGN FOR A PROJECTOR

Harold Osterberg, Buffalo, and Thomas G. Aitcheson, Tonawanda, N. Y., assignors to Spencer Lens Company, Buffalo, N. Y., a corporation of New York

Application March 29, 1940, Serial No. 91,331

Term of patent 14 years

To all whom it may concern:

Be it known that we, Harold Osterberg and Thomas G. Aitcheson, citizens of the United States of America, residing at Buffalo and Tonawanda, respectively, in the county of Erie and State of New York, have invented a new, original, and ornamental Design for Projectors, of which the following is a specification, reference being made to the accompanying drawing, forming a part thereof.

Fig. 1 is a side perspective view of a projector showing our new design;

Fig. 2 is a perspective view of the opposite side of the same as disclosed in Fig. 1; and

Fig. 3 is a top plan view of the same as disclosed in Fig. 1 and Fig. 2.

The characteristic features of the design are shown in full lines in the drawing.

We claim:

The ornamental design for a projector, substantially as shown and described.

HAROLD OSTERBERG.
THOMAS G. AITCHESON.
